CLAIM

I claim the ornamental design for a shoe, as shown and described.

DESCRIPTION

FIG. 1 is a front perspective view of a shoe, showing my new design;

FIG. 2 is a right side view thereof;

FIG. 3 is a left side view thereof; and,

FIG. 4 is a front view thereof.

The dot-dash broken lines define the bounds of the claimed design and form no part thereof. The remainder of the broken lines are for environmental purposes only and form no part of the claimed design.
